UNITED STATES PATENT OFFICE.

GEORGE H. WHEARY, OF RACINE, WISCONSIN.

WARDROBE-TRUNK.

1,093,225.

Specification of Letters Patent. Patented Apr. 14, 1914.

Application filed August 13, 1913. Serial No. 734,501.

To all whom it may concern:

Be it known that I, GEORGE H. WHEARY, a citizen of the United States, and resident of Racine, in the county of Racine and State 5 of Wisconsin, have invented new and useful Improvements in Wardrobe-Trunks, of which the following is a description, reference being had to the accompanying drawings, which are a part of this specification.

10 My invention has relation to improvements in trunks, and more particularly to trunks of the wardrobe type of construction.

In wardrobe trunks as ordinarily constructed, a wardrobe section is provided, 15 and this section is equipped in the upper portion thereof with rail sections forming a track from which clothes hangers are suspended, and upon which the said clothes hangers are movable inwardly and outwardly, the hangers being moved or adjusted outwardly when it is desired to gain access to the suspended clothing, and moved inwardly to a position within the wardrobe section during a time when access to the 20 suspended clothing is not desired or necessary, or in other words, when it is desired to close the wardrobe section preparatory to the shipment of the trunk.

The rails forming the track or runway 25 referred to usually consist of two parallel inner fixed rail sections and two outer movable rail sections hinged to the fixed sections, and adapted to be turned inwardly when it is not desired to gain access to the 30 clothing, but when the trunk is opened for use said hinged sections are adapted to be turned outwardly into alignment with the fixed rail sections so as to prolong or extend the track longitudinally and thereby provide 35 for pulling or moving the hangers outwardly from within the wardrobe section for ready and convenient access thereto.

In wardrobe trunks of the character referred to some provision is usually made 40 for holding the hangers, from which the clothing is suspended, firmly within the wardrobe section, so that the clothing will be held against movement inwardly and outwardly or upwardly and downwardly during 45 the shipment of the trunk. Heretofore this has been accomplished solely by providing the wardrobe section of the trunk

with a hinged top or lid provided on its under side with a yielding cushion, which, when the hangers are adjusted inwardly 55 into the wardrobe section and the said lid or cover is turned downwardly and secured, will bear yieldingly against the upper edges of the hangers and against the clothing suspended from said hangers, and thereby retain or hold the hangers and clothing against movement either inwardly or outwardly or upwardly or downwardly.

The object of my present invention is to provide an improved form of construction 60 adapted to accomplish the function of firmly and securely holding the hangers and clothing, without the necessity for providing a cushion upon the under side of a hinged top or cover, the construction being of such 65 character that it is immaterial whether the top of the wardrobe section is hinged or is fixed and rigid.

Before the adoption of the cushioned top or cover referred to, it was necessary to dispose the rails or trackway a sufficient distance below the under side of the top or cover of the wardrobe section as to leave a space sufficient for the movement inwardly and outwardly of the hangers and also sufficient 70 to provide room for the articles of clothing suspended from the hangers. Constructions of this character were open to the objection, that in the shipment of the trunk the hangers and clothing suspended therefrom were continually jumping upwardly and backwardly and forwardly. The cushioned top or cover, however, has obviated this difficulty, but the disadvantage of the cushion arrangement is that the top or cover 75 of the wardrobe section must necessarily be hinged, and in many cases it is desired in trunks of this character to construct the wardrobe section with a rigid top or cover. It will, therefore, be readily seen that a construction which will insure the firm retention 80 of the hangers and the clothing suspended therefrom in a wardrobe trunk, regardless of the fact as to whether the top or cover of the wardrobe section is hinged 85 or fixed, meets and fulfills a requirement not heretofore accomplished.

It is the object of the present invention, therefore, to provide a construction of such

character that the hangers and clothing suspended therefrom will be firmly retained and this without injury to the clothing, regardless of the fact as to whether the top or cover of the wardrobe section is hinged or fixed. In the present illustration of the invention the wardrobe section of the trunk is shown as provided with a hinged top or cover, but from what has been stated here-
tofore, it is to be understood that this top or cover may be fixed and rigid.

It is a further incidental object to provide a construction of the character referred to having such characteristics and peculiarities of construction that the sides of the wardrobe section are braced and held firmly against inward and outward deflection caused by variations or changes in temperature, or caused by rough handling.

With the above, and further incidental, objects in view, the invention consists of the devices and parts, or the equivalents thereof, as hereinafter more fully set forth.

In the accompanying drawings: Figure 1 is a vertical sectional view in elevation of a fragment of a wardrobe section of a trunk equipped with one form of my improvements, the top or cover being closed, and a fragment of the front cover of the wardrobe section being illustrated in dotted lines and as opened; Fig. 2 is a plan view, the top or cover being turned to open position and one of the hinged rails being shown in dotted lines as turned to an open position; Fig. 3 is a transverse section on the line 3—3 of Fig. 2, and on a plane at right angles to the plane of Fig. 1; Fig. 4 is a sectional view similar to Fig. 1, but showing a modified form of construction; Fig. 5 is a plan view of Fig. 4, the top or cover of the wardrobe section being shown in open position; Fig. 6 is a detail view, in side elevation, of a modified form of a hanger retaining mechanism, showing the same in locked position; Fig. 7 is a plan view of the modified form of hanger retaining mechanism, showing said mechanism adjusted to unlocked position; and, Fig. 8 is a detail fragmentary view of one of the hangers showing the manner in which it engages a rail section.

Referring to the drawings, the numeral 9 indicates an ordinary form of wardrobe section for a wardrobe trunk, being in the form of a rectangular box or casing, with a hinged top or cover 10, and a hinged front lid or cover 11. Extending forwardly from, and secured to, the rear wall of the casing, and having their front ends terminating substantially flush with the front edges of the side walls of the casing are the usual inner fixed track sections or rails 12—12. These fixed rail sections are of the usual construction, excepting that along their inner edges they are provided with notches 13, a notch of one rail section being opposite a notch of the

opposite rail section, and the several notches being preferably arranged equi-distant apart. The extreme outer ends of the fixed rail sections, as will be seen from the drawings, are without notches.

The hinged rail sections are indicated by the numeral 14, and the inner ends thereof are flattened and disposed between and pivoted to the members of the outer bifurcated ends of the fixed rail sections.

The numeral 15 indicates a transverse flat presser bar having on its front face loops 16—16 through which elongated locking dogs 17—17 pass and are guided thereby. The outer ends of the presser-bar 15 are formed with hooks 18—18 which fit loosely and slide over the adjacent rail sections. The inner ends of the two locking dogs are spaced a slight distance apart and are flanged or bent outwardly to form finger pieces 19—19. Disposed between and connected to, and acting expansively against these finger pieces, is a coiled spring 20 which normally holds the outer beveled ends of the locking dogs in engagement with oppositely disposed notches. It will be observed that the rear walls of the notches are beveled rearwardly so as to permit of the locking dogs and transverse presser bar, carrying such locking dogs, being pushed rearwardly or toward the back of the wardrobe section, without the necessity for manually releasing the locking dogs from engagement with the notches. When, however, it is desired to pull the transverse presser bar outwardly, it is then necessary to press the finger pieces of the locking dogs toward each other, against the contrary pressure exerted by the coiled spring, so as to release the outer ends of the locking dog from engagement with the notches.

Preferably the fixed rail sections 13 are secured rigidly to and extend forwardly from the rear or back member of a U-shaped strap 21, said back member of the strap being secured to the back of the wardrobe section, and the side members of the strap being secured to the sides of the wardrobe section. These fixed rail sections are supported near their forward ends by downwardly curved brackets 22 having their outer ends secured to the side members of the U-shaped strap, and their inner ends engaging beneath and supporting the rail sections.

In connection with the construction hereinbefore described, clothes hangers 23 are adapted to be employed, and these hangers are preferably of the form shown in Fig. 8 of the drawings, i. e., each hanger consists of an upper transverse member having hooks at opposite ends adapted to fit over the rail sections and slide freely thereon, laterally-extending and downwardly-inclined arms located immediately below the transverse member, a depending stem, and lower lat-

erally-extending arms at the lower end of the stem. Over the upper transverse member of the hanger, skirts and trousers may be suspended, and from the upper laterally-extending arms a coat, or similar garment may be suspended. It will be understood that a number of these hangers are arranged on the rail sections in the manner shown in Fig. 1, and after the clothes are suspended on the hangers, and it is desired to ship the trunk, the presser bar 15 is pushed toward the back of the wardrobe section, and this, of course, will force the several hangers firmly together and the beveled ends of the locking dogs will engage the notches of the rail sections and thereby hold the presser bar releasably in locked position against outward movement. When the hangers containing clothing are thus pressed and held together, it will be obvious that said hangers are firmly held in place against movement in any direction on the rail sections, and consequently the trunk can be shipped without danger of disarrangement of the clothing during shipment, or without danger of the clothing becoming accidentally disengaged from the hangers.

When it is desired to gain access to the clothing after the place of destination has been reached, the front cover of the wardrobe section is opened, and the hinged rail sections 14 pulled outwardly into alignment with the fixed rail sections. The finger pieces 19 are now grasped and pulled toward each other against the contrary action exerted by the spring 20. This will release the ends of the locking dogs 17 from engagement with the notches and permit of the presser bar 15 being pulled outwardly so as to release the hangers from their clamped condition. The hangers can then be pulled outwardly onto the hinged extension rail sections, and ready access thereby gained to any one or more of said hangers.

On Sheet 2 of the drawings, I show a modified form of presser bar locking mechanism. This modified form is of such character that the expense and labor incident to providing notches 13 along the inner edges of the fixed rail sections are obviated. In this form of construction, the presser bar 15 instead of having its ends provided with hooks fitting over the rail sections is preferably formed with openings 24 which are of sufficiently greater diameter than the rail sections as to provide for the presser bar moving freely along said rail sections. The locking dogs in this modification, consist of short plates 25—25 disposed at opposite ends and in front of the presser bar. These locking dogs are also provided with openings 26 through which the rail sections pass, said openings being but slightly greater in diameter than the rail sections so as to cause a firm binding against the rail sections when

the locking dogs or plates are tilted. It will be noticed that the outer ends of the presser bar immediately beyond the rail sections are flanged or bent forwardly at right angles, as indicated by the numerals 27—27. These flanged or bent ends are provided with openings 28 which receive the outer ends of the locking dogs 25, the said outer ends of the locking dogs having a slight play in the openings whereby a connection in the nature of a pivotal connection is formed between the locking dogs and the out-turned ends of the presser bar.

Connected to and extending forwardly from the presser bar, just inside of the rail sections, are short bolts 29—29, which bolts also pass through slightly elongated openings 30 in the locking dogs. Encircling each of these bolts and disposed between the outer head of the bolt and the outer face of the locking dog, is a coiled spring 31, which normally holds the locking dog in the position shown in Fig. 6 of the drawings. In this position the presser bar and the dogs carried thereby are locked against movement outwardly on the rail sections. Mechanism, however, is necessary for unlocking the presser bar after said bar has been adjusted inwardly against the suspended hangers, and when it is desired to unclamp the hangers, and thereby gain access to the clothing suspended on the hangers. For this purpose I provide a transverse dog-actuating rod 32, held to the presser bar in the guide loops or keepers 16. At its center this rod is provided with a looped handle 33, which, when it is desired to hold the presser bar in locked position, occupies the depending position illustrated in Figs. 4, 5 and 6 of the drawings. The outer ends of the rod 32 lie just back of the inner outwardly-deflected or slightly bent ends of the locking dogs, and these outer ends of the rod are bent at an oblique angle, as indicated by the numeral 34. When the handle 33 occupies the depending position shown in Figs. 4, 5 and 6, the bent ends 34 of the rod are out of contact with the inner ends of the locking dogs, as clearly shown. In this position, the expansive force of the springs 31 hold the locking dogs in the position shown, most clearly in Figs. 4 and 5, and in such position, the locking dogs are tilted, so that their outer ends are thrown slightly forwardly. This necessarily has the effect of firmly binding the bordering edges of the openings of the dogs against the rail sections, thereby firmly locking the dogs and presser bar against any forward or outward movement, while permitting at any time an inward movement so as to more tightly clamp the hangers, when necessary.

When the place of destination has been reached, and it is desired to gain access to the suspended clothing, the front cover of

- the wardrobe section is opened and the hinged rail sections turned outwardly into alignment with the fixed rail sections. The handle 33 is now grasped, and turned from its depending position shown in Fig. 4, to the horizontal position shown in Fig. 7. This will have the effect of turning the bent ends 34 of the rods outwardly and against the inner ends of the locking dogs, and therefore 10 by compress the coiled springs, and cause the locking dogs to be tilted or turned to the substantially straight position shown in Fig. 7. This has the effect of releasing the dogs from binding engagement with the rail sections, and consequently the presser bar and 15 dogs may be readily pushed inwardly or pulled outwardly as desired, the handle 33 forming a convenient means for thus moving the presser bar.
- From the foregoing description it will be seen that I provide simple and efficient mechanism for securely holding and retaining the hangers and clothes suspended therefrom within the trunk during shipment or transporation of the trunk as baggage, the said means also providing for readily gaining access to the hangers and the clothes suspended therefrom when the point of destination is reached, and it is desired to use the clothing.
- The mechanism is also of such character that the clothes are not in the least injured or damaged by the clamping mechanism. The mechanism herewith shown and described also provides a means for preventing outward or inward deflection of the sides of the wardrobe section, due to changes in temperature, or due to rough handling of the trunk. The devices which accomplish this are the brackets 22—22, which connect the side members of the U-shaped strap 21, with the rail sections 12. It is obvious that these brackets not only prevent outward movement of the sides of the wardrobe section, but also inward movement thereof.
- What I claim as my invention is:
1. In a wardrobe trunk, the combination of a wardrobe section, parallel rail sections located in the upper portion of the wardrobe section, and extending forwardly from the rear of said wardrobe section, and on opposite sides thereof, a presser bar mounted on said rail sections, and adapted to travel inwardly and outwardly thereon, locking dogs carried by said presser bar, means normally holding said locking dogs in engagement with the rail sections to prevent outward movement of the presser bar, and means, when operated, for releasing said locking dogs from engagement with the rail sections to permit movement inwardly and outwardly of the presser bar upon said rail sections.
  2. In a wardrobe trunk, the combination of a wardrobe section, parallel rail sections located in the upper portion of the wardrobe section, and extending forwardly from the rear of said wardrobe section, and on opposite sides thereof, a presser bar mounted on said rail sections, and adapted to travel inwardly and outwardly thereon, locking dogs tiltedly carried by the presser bar, said locking dogs provided with openings through
- section and extending forwardly from the rear of said wardrobe section, and on opposite sides thereof, a presser bar mounted on said rail sections, and adapted to travel inwardly and outwardly thereon, locking dogs carried by said presser bar, means also carried by the presser bar for normally holding said locking dogs in engagement with the rail sections to prevent outward movement of the presser bar, and means carried by the presser bar and adapted, when operated, to release the locking dogs from engagement with the rail sections to permit movement inwardly and outwardly of the presser bar upon said rail sections.
3. In a wardrobe trunk, the combination of a wardrobe section, parallel rail sections located in the upper portion of the wardrobe section and extending forwardly from the rear of said wardrobe section, and on opposite sides thereof, a presser bar mounted on said rail sections and adapted to travel inwardly and outwardly thereon, locking dogs carried by said presser bar, means normally holding said locking dogs in engagement with the rail sections, said means preventing outward movement of the presser bar, but permitting inward movement at all times, and means, when operated, for releasing said locking dogs from engagement with the rail sections, to permit free movement inwardly and outwardly of the presser bar upon said rail sections.
4. In a wardrobe trunk, the combination of a wardrobe section, parallel rail sections located in the upper portion of the wardrobe section and extending forwardly from the rear of said wardrobe section, and on opposite sides thereof, outer rail sections hinged to the fixed rail sections, and adapted, when turned outwardly, to be alined longitudinally with the fixed rail sections, a presser bar mounted on said rail sections, and adapted to travel inwardly and outwardly thereon, locking dogs carried by said presser bar, means normally holding said locking dogs in engagement with the rail sections, said means preventing outward movement of the presser bar, but permitting inward movement thereof at all times, and means, when operated, for releasing said locking dogs from engagement with the rail sections, to permit free movement inwardly and outwardly of the presser bar upon said rail sections.
5. In a wardrobe trunk, the combination of a wardrobe section, parallel rail sections located in the upper portion of the wardrobe section, and extending forwardly from the rear of said wardrobe section, and on opposite sides thereof, a presser bar mounted on said rail sections, and adapted to travel inwardly and outwardly thereon, locking dogs

- which the rail sections pass, means for normally holding the locking dogs in a tilted position so as to cause a binding of the bordering edges of the openings of the locking dogs against the rail sections, and thereby cause a locking of the presser bar and dogs against outward movement, and means for tilting the locking dogs to a substantially straight position to permit of free movement inwardly and outwardly on the rail sections of the presser bar and locking dogs.
6. In a wardrobe trunk, the combination of a wardrobe section, parallel rail sections located in the upper portion of the wardrobe section, and extending forwardly from the rear of said wardrobe section, and on opposite sides thereof, a presser bar mounted on said rail sections, and adapted to travel inwardly and outwardly thereon, locking dogs tiltingly carried by the presser bar, said locking dogs provided with openings through which the rail sections pass, bolts extending outwardly from the presser bar and through openings in the locking dogs, coiled springs disposed between the heads of said bolts and the outer sides of the locking dogs, said coiled springs by their expansive force adapted to normally hold the locking dogs in a tilted position so as to cause a binding of the bordering edges of the locking dogs against the rail sections and thereby cause a locking of the presser bar and dogs against outward movement, and means for tilting the locking dogs to a substantially straight position to permit of free movement inwardly and outwardly on the rail sections of the presser bar and locking dogs.
7. In a wardrobe trunk, the combination of a wardrobe section, parallel rail sections located in the upper portion of the wardrobe section, and extending forwardly from the rear of said wardrobe section, and on opposite sides thereof, a presser bar mounted on said rail sections and adapted to travel inwardly and outwardly thereon, locking dogs tiltingly carried by the presser bar, said dogs provided with openings through which the rail sections pass, means for normally holding the locking dogs in a tilted position, so as to cause a binding of the bordering edges of the openings of the locking dogs against the rail sections, and thereby cause a locking of the presser bar and dogs against outward movement, and a movable actuating rod carried by the presser bar, said rod, when actuated in one direction, being free from engagement with the locking dogs, to thereby permit the locking dogs to be normally held in locking engagement with the rail sections, and said actuating rod, when operated in an opposite direction, adapted to act against the locking dogs and cause said dogs to be thrown out of the tilted binding engagement with the rail sec-
- tions, to thereby permit the presser bar and dogs to be moved freely back and forth upon the rail sections.
8. In a wardrobe trunk, the combination of a wardrobe section, parallel rail sections located in the upper portion of the wardrobe section, and on opposite sides thereof, a presser bar mounted on said rail sections, and adapted to travel inwardly and outwardly thereon, said presser bar having its ends bent outwardly at an angle, the said angular ends being provided with openings, locking dogs carried by the presser bar, said locking dogs provided with openings through which the rail sections pass, and the outer ends of said locking dogs being mounted in the openings formed in the out-turned ends of the presser bar, bolts extending outwardly from the presser bar and through openings in the locking dogs, coiled springs disposed between the heads of said bolts and the outer sides of the locking dogs, said coiled springs by their expansive force adapted to normally hold the locking dogs in a tilted position so as to cause a binding of the bordering edges of the locking dogs against the rail sections and thereby cause a locking of the presser bar and dogs against outward movement, and a rocking rod carried by the presser bar, said rocking rod having its outer ends bent at an angle, and the rod, when turned in one direction, having said angular ends out of engagement with the locking dogs, so as to permit said dogs to occupy their normally tilted locking position, and said rod, when turned in an opposite direction, adapted to have its outwardly bent ends engage the locking dogs and turn said dogs to a substantially straight position, to permit of the free movement of the presser bar and locking dogs inwardly and outwardly upon the rail sections.
9. In a wardrobe trunk, the combination of a wardrobe section, parallel rail sections located in the upper portion of the wardrobe section, and extending forwardly from the rear of said wardrobe section, and on opposite sides thereof, a presser bar mounted on said rail sections, and adapted to travel inwardly and outwardly thereon, locking dogs carried by the presser bar, mechanism normally holding said locking means in engagement with the rail sections to prevent outward movement of the presser bar, and mechanism, when operated, for releasing the locking means from engagement with the rail sections to permit movement inwardly and outwardly of the presser bar upon said rail sections.
10. In a wardrobe trunk, the combination of a wardrobe section, parallel rail sections located in the upper portion of the wardrobe section, and extending forwardly from the rear of said wardrobe section, and on opposite sides thereof, a presser bar mounted on

6
said rail sections, and adapted to travel inwardly and outwardly thereon, means for releasably retaining or locking said presser bar in adjusted position upon the rail sections, and brackets having their inner ends connected to the rail sections and their outer ends connected to the sides of the wardrobe section, said brackets preventing outward

or inward deflection of the sides of the wardrobe section.

In testimony whereof, I affix my signature, in presence of two witnesses.

GEORGE H. WHEARY.
